(57) **CLAIM**

The ornamental design for a water closet, as shown and described.

DESCRIPTION

In a preferred embodiment, the nature of this product is as a plumbing fixture in the form of a water closet, a tank for a water closet, a cover for a water closet tank and a base for a water closet.

FIG. 1 is a right, top, front perspective view of a water closet base embodying my new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof; and,

FIG. 7 is a bottom plan view thereof.

The broken line representations of a bowl opening in FIGS. 2 holes in FIGS. 1-2, base structure in FIGS. 1, 3-4, and 7, underside features in FIG. 7, are for the purpose of illustration only, and form no part of the claimed design.
